STAY FOR UNIFORM CAP

Bernard Weinstein, Waban, Mass., assignor to Bancroft Cap Company, Framingham, Mass., a corporation of Massachusetts

Filed July 20, 1962, Ser. No. 211,202

1 Claim. (Cl. 2—195)

This invention relates to uniform caps of the type having a soft crown, and pertains more particularly to stays for supporting the forward part of the crown.

Uniform caps of the type to which this invention relates ordinarily include a stiff head band, to which a vizor is attached, and a crown consisting of a flat circular top panel and a side panel which flares outward toward the top and is usually somewhat higher at the front than at the rear. The crown may be permanently attached to the band or may be removable. To hold the top panel flat, a circular grommet of stiff material is often placed inside the top margin of the crown, and a stay may be mounted in the front to support the forward part of the crown. The stay also serves as a reinforcement in the front portion to receive insignia which are pinned or riveted to the cap.

The stays ordinarily used are rather narrow, straight pieces. If the crown is made of soft material the side panel tends to sag and become wrinkled on either side of the stay.

The principal object of this invention is to provide a cap stay which maintains a smoothly curved contour across the entire front portion of the cap. Another object is to provide a stay which can be used alone or in cooperation with grommets, top supports, and other stiffening members ordinarily used for maintaining the shape of uniform caps, which can be readily attached to the head band, which is adapted to receive insignia or other decorations and which can be manufactured inexpensively.

Other objects, advantages, and novel features of the invention will be apparent from the following description:

In the drawings illustrating the invention:

FIG. 1 is a plan view of a uniform cap equipped with a stay constructed according to the invention, with the crown removed;

FIG. 2 is an enlarged fragmentary cross-section taken along line 2—2 of FIG. 1, showing a removable crown and outer band in place on the cap; and

FIG. 3 is a front elevation of the stay prior to installation on a cap.

The head band assembly here illustrated consists of a stiff band 10 to the lower margin of which a sweat band 11 is stitched and folded up inside in the usual manner. A decorative braid 12 may be stitched to the folded lower margin of the sweat band, and a rigid vizor 13 is secured to the band assembly between the braid and the sweat band. The cap here shown is of the type having a removable crown and outer band assembly 14, constructed, for example, as shown in my U.S. Patent #2,844,824, utilizing a plastic strip 15 with an outwardly projecting bead 15a to hold the crown in place. It is understood, however, that a crown and outer band assembly may be permanently attached to the head band assembly in the

usual manner. The head band may have a strip of padding 16 attached between the band 10 and the sweat band.

The stay, generally indicated by the numeral 17, is a thin shell molded in one piece from plastic material which is rigid and resilient enough to hold its normal shape in ordinary handling, yet can be bent by hand to the extent necessary for assembly with other parts of the cap. The stay has an upper front portion 17a which is curved both from top to bottom and from side to side to conform to the shape which is desired for the forward part of the crown. Below portion 17a is a band portion 17b which is curved from side to side to fit the forward part of the head band assembly. A pair of wings 17c and 17d, which may be initially flat, extend from either side of portion 17b. Extending back from the upper edge of portion 17a are three tabs 18, 19 and 20. The band portion 17b has a center notch 21 to facilitate placing the stay in proper position.

To install the stay on the cap, the band portion 17b is fitted around the front of the band assembly, and wings 17c and 17d are bent back and fastened to band 10 at the sides by staples 24 (one of which is shown in FIG. 2), rivets, or other suitable means. If a grommet 22 is used in the cap, it is run under the tabs 18, 19, and 20, and tabs 18 and 20 may be bent down, as illustrated in FIG. 2, to secure the grommet in position. Tab 19 may be used for securing the forward end of a top stiffener 23 which is attached to the grommet at the rear.

In the finished cap, the crown 14 is supported by the stay over the entire forward portion above the vizor and held in a smoothly curved contour.

What is claimed:

In a uniform cap of the type having a generally circular head band, a soft crown with a front portion of arcuate shape and a top, a top stiffener underlying said top, and a grommet supporting the periphery of said top: a one piece stay comprising a curved band fitting around said head band below the front portion of said crown, a rigid crown supporting member extending upward from said band and supporting said entire front portion and being of smoothly curved shape corresponding to that of said forward portion, said member having an upper edge and being coextensive in the circumferential direction with said band, bendable side wings extending from said band 45 and secured to said head band at the sides thereof, and a central tab and bendable tabs to either side thereof extending rearwardly from the upper edge of said member, said central tab being secured to said top stiffener and said bendable tabs being bent down around said grom-
50 met.
